UNITED STATES PATENT OFFICE.

LIZZIE A. RINES, OF MINNEAPOLIS, MINNESOTA.

DESIGN FOR A DRESSMAKER'S RULE.

SPECIFICATION forming part of Design No. 29,134, dated August 2, 1898.

Application filed June 11, 1898. Serial No. 683,239. Term of patent 7 years.

To all whom it may concern:

Be it known that I, LIZZIE A. RINES, of the city of Minneapolis, Hennepin county, Minnesota, have invented and produced a certain new and useful Design for Dressmakers' Rules, of which the following is a specification, reference being had to the accompanying drawing, forming a part of this specification, and in which is shown a perspective view 10 of a dressmaker's rule of my design.

As shown in the drawing, the leading or material features of my design consist of a rule having a straight edge A, a second straight edge B, extending at right angles to said edge 15 A and of less length, a third straight edge C, extending at right angles to said edge B and of less length and parallel to said edge A, and a fourth straight edge H at right angles to said edge A and parallel with said edge B and 20 of a length about equal to said edge C, an ir-

regular curve D connecting the inside ends of the straight edges C and H, said irregular curve being of the form shown in the drawing, said rule being provided in its body portion with a slot E, the edges being in the form 25 of the irregular curves F and G, as shown, and the ends of the curves being connected with straight edges.

Having thus described my invention, I claim as new and desire to secure by Letters 30 Patent—

The herein-described design for a dressmaker's rule, substantially as shown and described.

In testimony whereof I have hereunto set 35 my hand this 16th day of April, 1898.

LIZZIE A. RINES.

In presence of—

ELLEN BUCKNAM,
FREDERICK S. LYON.
